MACHINE FOR MOLDING CONCRETE BRICK

Eugene De Luca, Philadelphia, Pa.

Application January 28, 1947, Serial No. 724,837

1 Claim. (Cl. 25—14)

2

My invention relates to the manufacture of brick and in particular refers to a rapid process for making concrete brick.

Heretofore, ordinary brick has been made by extruding a plastic mass of clay through a forming die, cutting the emerging clay strip into brick lengths, and firing these lengths in a kiln until they have hardened. This process is time-consuming, and the bricks frequently become misshapen from being cut and handled while still soft, resulting in waste.

An object of my invention is to provide a machine for producing concrete brick, which will remove the occluded air and water from the moist concrete strip by a vacuum process, thereby greatly reducing the time required for the bricks made therefrom to spontaneously harden. In addition, the machine will cut the strip into brick lengths without deforming them.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawing in which:

Fig. 1 is a sectional side elevation of my brick-making machine.

Fig. 2 is a detailed side section of the vacuum chamber.

Fig. 3 is an end view of the brick slicer.

Referring now in detail to my invention, wherein similar designations refer to similar parts, I prepare the concrete brick from a mixture of sand, cement, and water, into which coloring matter may be introduced if desired.

The plastic mixture is fed continuously into a mixing unit, generally designated as B. A screw 10 rotating within the unit B mixes the concrete thoroughly and extrudes the mass in a continuous strip through a forming neck or die 12, which has the cross-section of a brick. The neck 12 opens into a vacuum chamber, generally designated as D where the plastic mixture is substantially dried. This chamber is provided with exhaust valves 14 along its upper surface. The exhaust valves 14 are coupled all together or separately to a vacuum tank 16 by a corresponding number of tubes or pipes 18, only one of which is shown in the drawing. The tank 16 is maintained continuously at a vacuum by a pump (not

shown). As the moist concrete emerges from the neck 12 it passes between a pair of endless conveyor belts, generally designated as C and E, made of fabric, which conduct the strip along 5 the length of chamber D and finally through an outlet neck 20. During the passage of the strip along the chamber D, most of the air and water occluded in the mass are removed as vapor to the vacuum tank 16. Here some of the vapor 10 condenses as water and is tapped off at idle intervals through tap 23 in the tank 16, the remainder of the vapor being evacuated by a pump (not shown). The speed of the vacuum process may be varied by coupling more or fewer of the 15 valves on the tank 16 to the valves 14 in the vacuum chamber D, and by regulating the degree of vacuum generated by the pump (not shown). These adjustments are made according to 20 the speed of the moving concrete strip, its moisture content, and its consistency. The conveyor belts C and E serve not only to move the concrete strip but also are necessary to maintain its shape so that the concrete mass does not 25 disintegrate under the influence of the surrounding vacuum and its own internal content of air. The top of the concrete strip is engaged by the lowermost surface of the belt E. The members 30 maintain the tension of the upper belt E, so that the belt bears strongly against the surface 30 of the moving concrete strip.

The strip passing through the outlet neck 20 is very firm and compact but not completely solidified, and may be cut easily by a knife 24 mounted on a stand F without appreciable deformation. The strip itself seals the forming and outlet necks, 12 and 20 respectively, of the 35 vacuum chamber D against all but inconsequential air leakage.

40 The cutter 24 is located near the outlet of neck 20 and may consist of a cutter being eccentrically coupled to a drive shaft 26 by a connecting rod 28, as shown in Fig. 3, and adapted to cut the concrete strip into brick lengths. These 45 lengths may then be removed on another conveyor belt (not shown) to a location where they can solidify completely and of their own accord.

As is shown in the drawing, the mixer and extruder screw 10, the conveyor belts C and E 50 and the cutter 24 are geared or otherwise coupled to a single motor A. With this arrangement, all operations are synchronized regardless of the speed of the motor A, and no pile-up or jam can ensue. The vacuum pump (not shown) is regulated separately, taking into account both the

speed of motor A and the moisture content of the concrete mixture.

When properly manufactured, the concrete brick product is smooth and compact, possesses great compressive and sheer strength, and is both fireproof and waterproof.

Although my invention has been described in considerable detail, such description is intended as being illustrative rather than limiting, since the invention may be variously embodied, and the scope of the invention is to be determined as claimed.

I claim as my invention:

In a brick manufacturing machine, a concrete mixing and extruding chamber, a cross-section forming neck, a vacuum chamber, a plurality of taut conveyor belts arranged to convey and confine a concrete strip throughout said vacuum

chamber, a second forming neck, a brick-length cutter, and means for synchronizing the operation of said mixing and extruding chamber, said conveyor belts, and said cutter.

EUGENE DE LUCA.
